UNITED STATES PATENT OFFICE.

SYLVESTER L. JOINER, OF McGREGOR, TEXAS.

COMBINED GRAIN-DOOR STRIP AND SIDE-DOOR-POST PROTECTOR.

Application filed March 5, 1927. Serial No. 173,126.

The invention relates to a combined grain door strip and side door post protector.

The object of the present invention is to provide a simple, practical and efficient combined grain door strip and side door post protector of strong and durable construction adapted to be readily and cheaply manufactured and quickly assembled and applied to a box car interiorly thereof at opposite sides of the door opening to protect the side post of the box car and to support a wooden strip in position for enabling the boards of a grain door to be secured to it without the nails or other fastening means penetrating and injuring the side post of the car.

Another object of the invention is to provide a combined grain door strip and door post protector adapted to last the full life of a box car and capable of enabling the wooden strip which receives the fastening devices of the grain door to be readily removed and replaced by a new strip when necessary and capable of supporting and bracing the wooden strip at opposite sides thereof and of enabling a wooden strip to last for a considerable length of time so that it will not be necessary to renew the strip until the box car is overhauled or rebuilt.

The invention also has for its object to provide a grain door strip and door post protector adapted to serve as a shield or protection to prevent the hand trucks which are employed for loading and unloading the car from coming in contact with and cutting or otherwise injuring the wooden door post of the car and which will at the same time present rounded surfaces at the corners for contact with the hand trucks or other objects.

With these and other objects in view, the invention consists in the construction and novel combination and arrangement of parts hereafter fully described, illustrated in the accompanying drawings and pointed out in the claims hereto appended, it being understood that various changes in the form, proportion and minor details of construction, within the scope of the claims, may be resorted to without departing from the spirit or sacrificing any of the advantages of the invention.

In the drawings:—

Figure 1 is a longitudinal sectional view of a portion of a car provided with a combined grain door strip and side door post

protector constructed in accordance with this invention.

Fig. 2 is an enlarged detail perspective view of one end of the combined grain door strip and side door post protector, the filler strip being omitted for convenience of illustration.

Fig. 3 is a longitudinal sectional view of a portion of a car provided with a combined grain door strip and side door post protector and illustrating another form of the invention.

Fig. 4 is an enlarged detail perspective view of a portion of the combined grain door strip and side door post protector, the wooden post being omitted for illustrating the side bars more clearly.

Fig. 5 is a transverse sectional view of the device illustrating the manner of clamping and supporting the wooden filler strip shown in Fig. 3.

Referring particularly to Figs. 1 and 2 of the accompanying drawing the combined grain door strip and side door post protector consists of a pair of metallic side bars 1 located at opposite sides of and bracing and supporting a wood filler strip 2 and the said side bars 1 which form a metallic housing for the wood filler strip consist of angle bars having webs or flanges arranged at right angles to each other and rounded at their outer edges at the outer faces of the webs or flanges at 3 and 4 to present smooth surfaces to a hand truck or other object to prevent the same from catching on the combined grain door strip and side door post protector and injuring the same or being marred or otherwise injured by the device through such contact. The side bars 1 are arranged with their flanges 5 in parallelism at spaced relation to provide an intervening space for the reception of the wood filler strip which in the form of the invention illustrated in Figs. 1 and 2 of the drawing is secured in position between the side bars 1 by transverse bolts 6 piercing the flanges 5 and the wood filler strip and arranged at suitable intervals as indicated in Fig. 1 of the drawing. Any number of the transverse bolts 6 may of course be employed and the other flanges 7 of the angle side bars extend laterally from the flanges 5 and are fitted against the door post of the car 10 and are secured to the latter by wood screws 8 having flat heads countersunk in openings 9 in the

100
105
110

flanges 7 of the side bars. The screws 8 are arranged at suitable intervals and any desired number may be employed. The bolts 6 and the screws 8 are readily removable and the wood filler strip may be easily and quickly removed and replaced by a new filler strip when necessary. The boards 10^a for constituting the grain door are secured to the wood filler strip by nails 10^b or other suitable fastening devices in the usual manner as clearly illustrated in Fig. 1 of the drawing.

In Figs. 3 to 5 inclusive is illustrated another form of the invention in which the combined grain door strip and side door post protector is composed of spaced angle bars 11 and an interposed wood filler strip 12. The angle bars 11 which have webs or flanges arranged at right angles to each other are spaced apart to provide an intervening space for the wood filler strip 12 and the flanges 13 which are arranged in parallelism and which present flat surfaces to the sides of the wood filler strip are provided at their outer longitudinal edges with inwardly extending overhanging ribs or flanges 14 which extend over the marginal portions of the wood filler strip and fit in corresponding longitudinal recesses 15 thereof whereby the wood filler strip is securely fastened in position when the side bars 11 are secured to the car 16. The side bars 11 are rounded exteriorly at the outer edges of their webs or flanges 13 and 17 at 18 and 19 to present smooth exterior faces at the edges of the side bars to prevent hand trucks and other objects which may come in contact with the combined grain door strip and side door post protector from being marred or otherwise injured by the device of the present invention and also to avoid injury to the said device. The flanges 17 which extend laterally from the flanges 13 are fitted flat against the door post of the car 16 and are secured to the same by wood screws 20 which are arranged in countersunk openings 21 in the webs or flanges 17. The overhanging ribs formed by extending the flanges 13 inwardly obviate the necessity of employing transverse bolts for securing the wood filler strip between the side bars and they also avoid piercing the wood filler strips for the said bolts. While the outer portion of the wood filler strip 12 is reduced in width by the recesses 15 the metallic ribs fill the recesses and brace and support the said strip 12 adjacent the outer face of the same. This construction also enables the filler strip 12 to be readily removed and replaced by a new filler strip when required. The angle

bars which form the sides and constitute the 60 metallic housing for the wood filler strips and the said filler strips may be made of any required dimensions. The wood filler strip is adapted to receive fastening devices 22 of the boards 23 which constitute the grain 65 door as clearly illustrated in Fig. 3 of the drawing.

What I claim is:

1. A combined grain door strip and side door post protector located interiorly of the car at the side of the door opening and comprising spaced relatively heavy angle bars forming a sectional metallic housing and having angularly related webs and provided with inwardly extending longitudinally disposed flanges projecting from one of the webs over the intervening space between the angle bars the other web of each bar forming an attaching portion, and a wood filler strip arranged between the angle bars and 70 confined in the space between the same by the said longitudinal flanges, the sectional metallic housing permitting ready removal and replacement of the wood filler strip, said wood filler strip being provided at its outer portion with side marginal recesses receiving the longitudinal flanges of the angle bars and forming a reduced intermediate portion arranged in flush relation with the outer faces of the flanges, said angle side 75 bars being rounded exteriorly at the outer edges of both of the webs to form rounded exterior surfaces at the corners of the combined grain door strip and side post protector and at the attaching portions thereof.

2. A combined grain door strip and side door post protector located interiorly of the car at the side of the door opening and comprising a sectional metallic housing composed of spaced relatively heavy angle bars 80 having angularly related webs, a wood filler strip arranged between and filling the space between the angle bars and adapted to receive the fastening devices for securing a grain door to the car, and means carried by 85 the webs of the angle bars for securing the latter to the car and for holding the filler strip in position between the angle bars the sectional metallic housing permitting the ready removal and replacement of the wood 90 filler strip, said angle bars being rounded exteriorly at the outer edges to present rounded surfaces at the corners of the combined grain door strip and side door post 95 protector.

In testimony whereof I have hereunto set my hand.

SYLVESTER L. JOINER.
